UNITED STATES PATENT OFFICE.

EARL ENGLER SNADER, OF WEBSTER GROVES, MISSOURI.

AUTOMATIC TEMPERATURE-ACTUATED REFRIGERANT-REGULATING VALVE.

Application filed June 9, 1926. Serial No. 114,726.

This invention relates to an automatic regulating valve for use in automatic refrigerating systems for rooms where two or more units are fed by one automatic expansion valve as in the case of direct expansion systems.

Briefly, the improved valve embodies an especially constructed casing with which sections of the main refrigerant line are connected, there being a slotted cylinder arranged in the path of travel of the refrigerant together with a slotted sleeve arranged in this cylinder, the sleeve being moved in one direction by spring pressure and in an opposite direction by an automatically operable thermostat.

The particular details and their relative arrangement and association will be made apparent by considering the following description and drawing.

In the drawing:—

Figure 1 represents a view in section and elevation of a regulating valve constructed in accordance with this invention.

Figure 2 is a section on the line 2—2 of Figure 1.

Fig. 3 is a diagrammatic view showing two of the valves in the system.

Referring to the drawing in detail, the reference character 1 designates generally the casing which is somewhat globular in general configuration, the same being provided on its interior with a partition 2 and at its ends with pipe connections 3 and 4 respectively. It might be stated here that the main refrigerant line is connected with the connection 3 and the refrigerant passes therethrough in a direction from left to right and discharges through a main refrigerant conducting pipe which is also connected with the connection 4. The casing includes an upstanding neck 5 provided with an annular groove in its top for accommodating a supporting flange on a ring-like head 6. Depending from this head is a cylindrical valve guide 7, which as before stated, is provided with slots arranged in superposed vertically spaced relation to form ports for passage of the refrigerant.

A slidable valve sleeve 8 is fitted snugly and slidably in this guide and includes slots adapted to register with those in the guide. The valve sleeve is ordinarily pressed upwardly by a coiled spring 9, the tension of which is adjusted by a hand wheel 10.

Resting on an upstanding circular rib on

top of the head 6 is a diaphragm 11 which in turn supports an annulus 12. Moreover, the annulus in turn supports another diaphragm 13 and suitable packing material 14 is confined within this annulus and between the two diaphragms.

As before stated, the valve sleeve is moved in one direction by a thermostat 15 of the bellows type, or other temperature actuated contracting and expanding element. This thermostat is provided with a suitable protecting casing 16 where necessary, having a flexible diaphragm end bearing on diaphragm 13 which in turn bears on stem 17, which in turn bears on diaphragm 11, which is in bearing contact with the top portion of slideable sleeve 18. It is to be noted that there is no connection between the thermostat casing and sliding sleeve other than the bearing upon and thereby being in contact with it through the stem 17 which is an independent piece to maintain the same space between the diaphragms under all conditions. The thermostat and its casing are arranged in an appropriately designed housing 19 having a base 20 suitably connected in place. In addition, this housing includes a screw threaded portion 21 and 22 which in practice connects a box coil to valve housing 19 and from the valve housing to a point just beyond the regulating valve, on the main refrigerating line respectively.

It will be obvious to those skilled in the art to which the invention relates that the regulating valve is installed in the main refrigerant line 23 on the discharge side of the expansion valve 24. Moreover, it is obvious that the fluid passes from the compressor pump 25, through the condenser 26, receiver 27, and piping 28 to and through the expansion valve in direct expansion systems, or cooler in brine systems, and enters the valve at a point 3 and passes through the registering slots in the valve and valve guide and out through the discharge 4. However, since one end of the piping of the box coil 29 is connected with the housing 19 at 21, it is obvious that the temperature will serve to automatically expand and contract the thermostat 15 in an obvious manner. As shown in the drawing, the thermostat is contracted and therefore the valve 8 is completely open. However, when it is expanded from a rise in temperature, the valve sleeve moves downwardly against the tension of the spring 9 and partially or completely cuts off the flow

of fluid through the valve according to the particular conditions experienced. The valve is of course primarily intended to produce a throttling effect in the system and it is not intended to provide a gas-tight or fluid tight valve, but merely one which will generate enough friction to shunt a part of the refrigerant through the coil. It will be noted that the chamber in the housing 19 in which the thermostat is located is exposed to the temperature of the returning refrigerant, and it is obvious that when the return refrigerant is cold, the room is proportionately cool, and when the temperature of the return refrigerant rises, a degree or more, the room temperature rises proportionately. While the drawing shows the thermostat fully contracted, it is obvious that at the time the cooling process is started in the room, the thermostat will be expanded, and in so doing will push the valve sleeve downward, substantially closing the control valve.

The method of installation and operation, together with the arrangement of details is no doubt clear from the description. Therefore, a more lengthy disclosure is deemed unnecessary.

Minor changes coming within the field of invention claimed may be resorted to if desired.

Having thus described the invention, what

I claim as new and desire to secure by Letters Patent is:—

1. In an automatic regulating valve of the class described, a casing having a partition therein, a cylindrical valve guide extending through an opening formed in said partition, said guide being provided with slots, a spring pressed valve sleeve slidably mounted in said guide and having slots cooperating with the first named slots, a pair of spaced flexible diaphragms, a thermostat bearing on said valve sleeve through the medium of said diaphragms for moving the sleeve in a direction against the tension of the spring. 45

2. In an automatic regulating valve of the class described, a casing having a partition therein, a cylindrical valve guide extending through an opening formed in said partition, said guide being provided with slots, 50 a spring pressed valve sleeve slidably mounted in said guide and having slots cooperating with the first named slots, a pair of spaced flexible diaphragms, a thermostat bearing on said valve sleeve through the medium of 55 said diaphragms for moving the sleeve in a direction against the tension of the spring, and a housing for said thermostat provided with pipe connections for subjecting the thermostat to varying temperatures. 60

In testimony whereof I affix my signature.

EARL ENGLER SNAIDER.
